SANDWICH WRAPPING MACHINE

Ernest Sigsbee Wollett, Washington, D. C.

Application November 24, 1948, Serial No. 61,841

35 Claims. (Cl. 53—131)

The present invention relates to improvements in article or package wrapping machines and is directed primarily to improvements in machines for wrapping bodies of a particular form, more especially sandwiches.

A principal object of the present invention is to provide a fully automatic wrapping machine designed to completely wrap and seal bodies of material of substantially triangular or wedge form.

Another object of the invention is to provide a fully automatic machine designed to completely wrap and seal bodies of material of a soft yieldable character, without the use of a supporting backing.

Another object of the invention is to provide a machine of the character stated for wrapping bodies of triangular form, especially sandwiches.

A further object of the invention is to provide, in a machine of the character set forth, a novel automatic wrapper feeding mechanism whereby the required length of wrapping material is withdrawn and cut from a roll and wherein the length of the wrapping material may be increased or decreased by shifting the feeding mechanism with respect to a constantly rotating actuator element.

A still further object of the invention is to provide a machine for wrapping triangular cut sandwiches whereby the sandwiches are handled individually throughout the wrapping steps and are delivered in rapid sequence but spaced apart so that there is no crowding and mashing together of the sandwiches at any time.

Still another object of the invention is to provide an automatic wrapping machine of the character stated for wrapping bodies of triangular form which are made up of a number of layers, such as sandwiches, with means for lightly gripping the body preliminarily to applying the wrapping sheet, to hold the layers together while the first step of applying and folding the wrapping sheet is being performed.

Still another object of the invention is to provide a fully automatic wrapping machine of the character stated designed to completely wrap and seal soft, yieldable bodies of the form described in slightly varying sizes.

A still further object of the invention is to provide a fully automatic wrapping machine for folding and sealing bodies of the character stated, in a thermoplastic wrapper in a manner to prevent the wrappers of successive bodies from adhering together.

Still another object of the invention is to provide a fully automatic wrapping machine for bodies, particularly sandwiches, with novel means for transferring the body from a carriage to a wrapper folding position without damage to the body.

Still another object of the invention is to provide a fully automatic machine for wrapping bodies, particularly sandwiches, with novel means for transferring the body from a carriage to a wrapper folding position without damage to the body, and subsequently folding a wrapper around the body and sealing the wrapper, without the use of a backing or stiffening means for maintaining the shape of the body.

Still another object of the invention is to provide a machine for wrapping bodies of a soft character, such as sandwiches, with novel means for transferring the body from a carriage to a wrapper folding position, without damaging or deforming the body, and for locating and holding the body in the said position to which it is transferred, while the transferring means is withdrawn, to permit the subsequent operation of a folder element which

2

functions to turn a part of the wrapper around a part of the body.

Still another object of the invention is to provide a fully automatic machine for wrapping bodies of substantially triangular form such as sandwiches, with means for transferring the body from a carriage to a wrapper folding position and means for automatically positioning a wrapper sheet in the path of travel of the transferring means whereby the wrapper is picked up and carried with the body, and partly folded about the body, to the said wrapper folding position.

A still further object of the invention is to provide a machine of the character stated for performing the operations set forth in the preceding paragraph with automatically operating means for withholding the placement of a wrapper sheet in the path of travel of the said body transferring means upon the failure of the carriage to present a body for transfer.

Another object of the invention is to provide a fully automatic machine for wrapping bodies of the character stated, particularly sandwiches, with novel means for folding a wrapper sheet over the body and for drawing the sheet smoothly and tightly about the body without deforming the body, while the edges of the wrapper sheet are folded in one over the other and sealed to form an air-tight package.

Still another object of the invention is to provide, in a machine of the character stated, a novel means for automatically drawing-off and cutting from a roll, a wrapping sheet of desired size and locating the sheet in predetermined position to be picked up by the body as the body is moved into a wrapping position.

A still further object of the invention is to provide an automatic wrapping machine for bodies of substantially triangular form, particularly sandwiches cut diagonally in two parts and placed one part upon the other to form a triangular body, with a carriage means for moving the triangular bodies in successive steps to a prescribed position with the point formed by the intersecting perpendicular edges directed downwardly, means for positioning a rectangular wrapping sheet over the upwardly directed edge of the body, means for gripping the body and moving it against the wrapper and then moving the body and wrapper together between spaced members to fold the wrapper down against the sides of the body, and means for then folding over and sealing the edges of the wrapper to form the completed package.

In the drawings:

Figure 1 is a view in top plan of a machine constructed in accordance with the present invention.

Figure 2 is a view in elevation of the rear or back end of the machine.

Figure 3 is a view in elevation of the left side of the machine upon which side the paper feed mechanism, which is deleted from this view, is located.

Figure 4 is a view in elevation of the right hand side of the machine with some of the baskets of the rotary carriage removed.

Figure 5 is a vertical section taken substantially on the line 5—5 of Figure 4, with certain of the parts omitted for clarity.

Figure 6 is a horizontal section taken substantially on the line 6—6 of Figure 4 with certain of the parts omitted.

Figure 7 is a vertical section on an enlarged scale, taken substantially on the line 7—7 of Figure 1.

Figure 8 is a detail section taken substantially on the line 8—8 of Figure 7 showing the elevator and grippers in the basket.

Figure 9 is a sectional view on an enlarged scale corresponding to Figure 7 but showing the parts advanced through the basket.

Figure 10 is a transverse section taken substantially on the line 10—10 of Figure 9.

Figure 11 is a transverse section taken substantially on the line 11—11 of Figure 9.

Figure 12 is a sectional view corresponding to Figure 7 showing the relative positions of the elevator and gripper after the sandwich has been delivered into the receiver.

Figure 13 is a sectional view corresponding to Figure 12 but showing the preliminary advance of the slideable

folder to maintain the sandwich in position when the elevator retreats.

Figure 14 is a transverse section on an enlarged scale through a press plate and the supporting bar therefor.

Figure 15 is a sectional view corresponding to Figure 13 but showing the wrapper folding plate in fully extended position.

Figure 16 is a sectional view corresponding to Figure 15 but showing the sandwich being shifted from the receiver and the under folding of the remaining portion of the wrapper.

Figure 17 is a horizontal section taken substantially on the line 17-17 of Figure 7.

Figure 18 is a detail section taken substantially on the line 18-18 of Figure 17.

Figure 19 is a detail section taken substantially on the line 19-19 of Figure 17.

Figure 20 is a vertical section taken substantially on the line 20-20 of Figure 12.

Figure 21 is a transverse section taken substantially on the line 21-21 of Figure 7.

Figure 22 is a transverse section taken substantially on the line 22-22 of Figure 7.

Figure 23 is a transverse section taken substantially on the line 23-23 of Figure 7.

Figure 24 is a transverse section taken substantially on the line 24-24 of Figure 7.

Figure 25 is a view in plan of the basket carriage rotating mechanism, the basket plate and baskets being removed.

Figure 26 is a sectional view taken substantially on the line 26-26 of Figure 25.

Figure 27 is a detail view partly in plan and partly in horizontal section of a portion of the carriage plate supporting elements and the rotating mechanism therefor.

Figure 28 is a vertical section taken substantially on the line 28-28 of Figure 27.

Figure 29 is a sectional view taken substantially on the line 29-29 of Figure 28.

Figure 30 is a view in side elevation of a sandwich basket.

Figure 31 is a view in end elevation of the same.

Figure 32 is a view in top plan of the basket.

Figure 33 is a transverse section on the line 33-33 of Figure 32.

Figure 34 is a longitudinal section on the line 34-34 of Figure 32.

Figure 35 is a view in top plan of the wrapper cutter unit per se.

Figure 36 is a view in elevation of one side of the wrapper cutter.

Figure 37 is a view in elevation of the opposite side of the wrapper cutter.

Figure 38 is a view in elevation of the knife or cutter end of the wrapper cutter.

Figure 39 is a longitudinal section taken substantially on the line 39-39 of Figure 35.

Figure 40 is a transverse section taken substantially on the line 40-40 of Figure 35.

Figure 41 is a sectional view taken substantially on the line 41-41 of Figure 6 showing the driving connections for the wrapper cutting and feeding unit.

Figure 42 is a longitudinal section taken on the line 42-42 of Figure 3, through the yielding pitman coupling.

Figure 43 is a horizontal section on the line 43-43 of Figure 5.

Figure 44 is a vertical transverse section taken on the line 44-44 of Figure 9.

Figure 45 is a detail view partly broken away of electromagnet control unit for the wrapper feed.

Figure 46 is a view in perspective of a sandwich wrapped by the machine, showing the one of the two right angle sides thereof against which the tail end of the wrapper is folded.

Figure 47 is a view corresponding to Figure 46 but showing the other one of the two right angle sides.

Referring now more particularly to the drawings reference will first be made to the frame structure of the machine together with the power mechanism supported thereby.

The numeral 10 generally designates the frame minus the major portion of the covering or housing which, in the completed machine, will be employed for covering or protecting the working or moving parts of the mechanism. Such frame comprises front uprights or posts 11

and rear posts 12. The front posts are connected to the rear posts by the horizontal side beams 13 and transverse front and rear end beams 14.

The numeral 15 generally designates the horizontal top frame structure which with its associated parts will be hereinafter more fully described.

Suitably supported or mounted in the lower part of the structure as, for example, upon the hanger 16, is an electric motor 17 and adjacent thereto is a suitable speed reduction mechanism 18 of standard construction, with the shaft 19 of which the motor 17 is connected. The numeral 20 designates the power delivering shaft of the speed reduction unit.

Disposed transversely of the machine at the rear end thereof and above the motor 17 is a counter shaft 21 which is rotatably supported in suitably mounted bearings 22. This counter shaft is in driving connection with the shaft 20 by a chain and sprocket coupling 23. Adjacent to the vertical central plane of the machine are the two cams 24. Also secured to the shaft adjacent to the left side thereof is a cam 25.

Adjacent to the opposite side of the machine the shaft carries the two sprocket gears 26 and 27.

Supported upon a suitable mount, here designated as a plate 28, located at an elevation below the counter shaft 21 is a rocker arm supporting shaft 29 which is carried in suitable spaced bearings 30. This shaft is parallel with the counter shaft 21 and upon it are oscillatably supported the rocker sleeves 31 to each of which is rigidly secured an end of a vertically swingable lift or rocker arm which extends to the front of the machine as shown in Figure 3.

Also rigidly secured to each of the bearing or rocker sleeves 31 and extending upwardly at substantially right angles to the arms 32, is a cam follower arm 33, which has rotatably mounted upon its upper end the cam follower roller 34 which bears against the back edge of an adjacent cam 24. Accordingly it will be seen that the tendency of the arms, which are of substantial length, to swing downwardly maintains the cam follower rollers 34 constantly in engagement with the periphery of an adjacent cam 24.

The numeral 35 designates a short shaft which is in parallel relation with the countershaft and is mounted between bearings 36 suitably secured to and supported by a horizontal side rail upon the right hand side of the machine. This short shaft 35 has oscillatably supported thereon a bell crank having a long upwardly extending arm 37 and the short forwardly and downwardly extending cam follower arm 38 upon which is rotatably mounted the cam follower roller 39 which bears against the forward side of the cam 25 as clearly shown in Figure 6. The short arm 38 has connected therewith one end of a spring 40 which extends downwardly and has its other end secured to an adjacent part of the frame, whereby the bell crank is constantly pulled in a direction to maintain the cam follower roller 39 in contact with the adjacent cam 25 and to maintain the long arm 37 thrust forwardly when the roller 39 is at the low point of the cam.

At the right hand side of the machine and adjacent to the front thereof, there is mounted the horizontal plate 41 upon which is mounted and secured a gear unit which is generally designated 42, the details of which are best seen in Figures 25 to 29 inclusive. By means of this unit operating power is transmitted in two directions for the operation of the hereinafter described rotary and intermittently moved carriage structure and the wrapping material feeder and cutter unit.

As shown in Figure 26 this unit 42 comprises a vertical housing 43, preferably of cylindrical or tubular form, having the radially directed integral collars 44 and 45 which are spaced apart in a clockwise direction, as shown in Figure 25, approximately 135°. In the set up position of this unit the collar 44 is directed straight outwardly toward the right side of the machine and accordingly it will be seen upon reference to Figures 4 and 6 that the other collar 45 is directed obliquely across the machine toward the front end thereof. The purpose for this arrangement will become apparent as the description of the operation of the wrapping material feeder and cutter unit is given.

Mounted in the upper and lower ends of the housing 43 are bearings 46 in which are rotatably mounted the vertical shaft 47. This shaft has secured thereto in

spaced opposed relation, the upper and lower bevel or mitre gears 48 and 49 respectively.

Fixed upon the upper end of the shaft 47 is a sleeve 50, the top end of which is formed to provide the circular head 51 which has formed therein the deep radially directed recess 52. This head functions as a lock for the hereinafter described carriage structure.

Integral with the top of the head 51 is a crank arm 53 which turns or rotates in a horizontal plane and the outer end of this arm, which extends beyond the periphery of the head 51, carries an anti-friction roller 54 for the purpose hereinafter described.

Collar 44 has rotatably mounted therein as shown in Figure 26, the stub shaft 55 on the inner end of which is secured the mitre gear 56 which is positioned within the housing 43 and is in toothed connection with the lower mitre gear 49.

Upon the outer end of the stub shaft 55 is a sprocket gear 57 which has connected therewith the sprocket chain 58 which passes around the sprocket gear 27 mounted upon the counter shaft 21 as shown in Figure 6.

The numeral 59 designates an idler gear which is mounted upon an adjacent part of the machine frame as shown in Figure 4.

Upon a cross bar 60 which supports the forward ends of the two spaced beams 22' which carry the counter shaft bearings 22, is mounted an upright 61. Secured to the upright 61 is an arm 62 which extends obliquely across the machine toward the front left hand side as shown in Figure 6. This arm 62 supports an end of a platform 63 the opposite end of which is mounted upon a top side beam 13 of the frame. From the under side of this platform is hung a plate 63' upon the underside of which are suspended in inverted position, spaced bearings 64 which support a short counter shaft 65, as shown in Figure 41.

The shaft 65 carries three sprocket gears 66, 67 and 68, see Figure 41.

The shaft 65 is positioned to extend in a direction oblique to the length of the machine and in parallel relation with this shaft is the stub shaft 69 which is rotatably supported in suitable bearings in the collar 45 of the housing 43. This stub shaft carries upon its inner end the mitre gear 70 which is disposed within the housing 43 and is in toothed connection with the upper one of the two gears in the housing, that is, the gear 48.

Upon its outer end the shaft 69 has secured thereto the sprocket gear 71 and this gear is in driving connection with the gear 66, by means of the sprocket chain 72.

From the description as thus far given it will be seen that upon rotation of the counter shaft 21 through the medium of the sprocket and gear connection 23, the cams 24 will effect the vertical oscillation of the arms 32 and the cam 25 will effect the oscillation of the bell crank arm 37, for the purposes hereinafter described. Also power will be transmitted by way of the sprocket chain 58, to the gear 57 of the distributing unit 42 to effect the rotation of the vertical shaft 47 of such unit. This will impart rotary motion to the crank 53 for the intermittent or step-by-step rotation of the carriage structure about to be described and it will also effect rotation of the stub shaft 69 to transmit rotary motion to the shaft 65 for the operation of the hereinafter described wrapping material feeder and cutter unit.

Rotary carriage structure

Adjacent to the front right hand corner of the frame structure there is mounted upon the plate 41 and held in vertical position between such plate and the overlying plate member 73 which is connected to the adjacent corner post of the frame, the tubular housing 74. In the upper and lower ends of this housing are secured, as shown in Figure 5, suitable bearings 75 and 76 respectively which support the vertical spindle 77. The upper end of this spindle has secured thereto the rotary carriage structure which is generally designated 78.

The rotary carriage, in the form here illustrated, comprises three superposed plates designated 79, 80 and 81. For purposes of differentiation the plate 79 will be referred to as the basket plate, the plate 80 as the crank plate and the plate 81 as the lock plate.

As shown in Figure 25 the peripheries of the plates 80 and 81 pass over the axial center of the vertical shaft 47. The lock plate is formed with a scalloped edge so that

there are provided, as shown in Figure 25, the adjacent semi-circular recess 82 which are separated by points 83. These recesses are of a radius corresponding to the radius of the circular head 51 and the positioning of the lock plate with respect to the head 51 is such that in the step-by-step rotation of the carriage the head 51 will move into and rotate in succeeding recesses, shifting from one recess to the next by receiving in the head recess 52 the point 83 which separates the recess 82 in which the head 51 has just been located, from the recess 82 into which the head is moving.

The plate 80 is of approximately the same or slightly greater diameter than the plate 81 and secured to or formed integral with the under face of this plate 80 are the spaced wedge shaped blocks 84. The spacing of these blocks 84 provides a plurality of straight crank slots 85, the sides of which are in spaced parallel relation and the radial center of each of which passes through the radial center of the spindle 77 as shown in Figure 25. The width of each crank slot 85 is substantially the same or only slightly greater than the diameter of the crank roller 54 which the slot receives. Also the plates 80 and 81 are fixed so that the center of each point 83 of the lock plate 81 lies exactly in the center of a crank slot 85 as is clearly shown in Figures 25 and 27. Accordingly it will be understood that when the crank arm 53 is directed radially inwardly as shown in Figure 27, it will be at its innermost position in a slot 85 and the point 83 underlying such slot will be directly in the center of the recess 52 of the head 51 as shown in Figure 29 so that the head is ready to turn into the next recess 82 in which it will fit to hold the carriage against movement after the crank roller 54 has left the slot 85 and during the period that the crank is passing through the major portion of its rotary movement.

As shown in Figure 5 the top or basket plate 79, which is secured to the underlying plate 80, extends a slight distance beyond the periphery of the crank plate 80. This extended peripheral portion of the basket plate 79 facilitates the attachment to such plate of a plurality of radially disposed rectangular baskets, each of which is generally designated 86 and one of which is shown in detail in Figures 30 to 34 inclusive. As illustrated in the above stated figures the basket, which is designed to receive a triangular cut sandwich with the point of the triangle directed downwardly and the base facing upwardly and disposed in a horizontal plane, comprises the rectangular frame 87 across one end of which is formed the mounting flange or lip 88. This flange or lip, as best seen in Figure 5, engages under the peripheral portion of the plate 79 and is secured thereto by a pair of bolts 89 which are threaded into suitable apertures in the plate 79 and pass through the apertures 90 in the flange.

Disposed vertically against the inner sides of the frame 87 are the vertical wall strips 91. These strips are mounted against the longitudinal sides of the frame in such a manner as to stand inwardly a substantial distance therefrom. In addition to the strips 91 on each side of the frame being spaced apart as illustrated, each is spaced a substantial distance from the transverse end portion of the frame so that there are provided vertical guide passages at each side of the basket as indicated at 92.

The upper ends of the wall strips 91 are curved outwardly slightly as indicated at 93 to facilitate the placing of a sandwich in the basket.

The inner faces of the strips 91 have formed lengthwise thereof below the out-curved upper ends 93, the ribs 94. These ribs facilitate the placing and maintenance in the basket of sandwiches which may be of varying thickness according to the filling which the same carry.

At each end of the frame 87 is an upwardly and outwardly inclined rest plate 95, each side of each plate having the upwardly and outwardly curving wings 96. As will be readily apparent these rest plates 95 have the under inclined edge of the sandwich bearing or resting thereon and the wings 96 cooperate with the out-turned ends 93 to support the adjacent sides of the sandwich.

The baskets are secured in side-by-side relation as clearly shown in Figure 1 to extend radially of the carriage plates and with each rotary step of the carriage structure a basket will be brought into a prescribed position on a line extending transversely of the machine where it will be held for a desired period of time by the engagement of the head 52 in a recess 82. When the

basket is in such prescribed position its transverse center will be on the longitudinal center line of the machine as shown in Figure 1.

For the purpose of protecting operators of users or the machine and to prevent damage to the baskets, a circular guard rail 97 is secured horizontally to the frame of the machine substantially in the horizontal plane of the top edges of the baskets.

Elevating mechanism and wrapper table

In the longitudinal center of the machine and in line transversely thereof with the center of the carriage spindle 77 or, in other words, with the plane of the axis of rotation for the carriage structure is located the elevating mechanism by means of which each sandwich is removed from its basket as it is brought into the said predetermined position.

At the front end of the machine there are secured to two vertically spaced cross beams or rails 14, inwardly extending bracket arms 99. These bracket arms support upper and lower guide plates 100 and 101 respectively which are connected together by vertical tie bolts 102. These guide plates 100 and 101 have guide openings 103 which are in vertical alignment as best shown in Figure 5. In addition to these vertically aligned openings 103, the upper guide plate 100 has formed therethrough the spaced openings 104, as shown in Figure 8.

Secured upon an adjacent part 105 of the frame, as shown in Figure 7, in a horizontal plane lying just above the horizontal plane of the tops of the baskets, is a perforated wrapper sheet supporting table 106 which has therein a rectangular opening 107, the length of which extends transversely of the machine as shown in Figures 1 and 6 and the longitudinal center of which is in a vertical plane transversely of the machine and to one side of the rotary center of the basket carriage structure. As is also clearly shown in Figure 6 the center of this table opening 107 is directly in line with the aligned openings 103 of the upper and lower guide plates 100—101.

Disposed vertically through two of the aligned openings 103 is a rod 109 and through the other pair of vertically spaced and aligned openings 103 is a similar or corresponding rod 110. The rod 109 constitutes what may be termed the gripper rod and the rod 110 the elevator rod. These rods, as shown in Figure 8, are of hexagonal cross section and mounted upon the top side of each of the guide plates 100 and 101 is a group of three rollers which are equi-distantly spaced around the rod 109 and bear against one of the faces thereof. Likewise, in association with the rod 110 there is a group of three rollers 112 secured to the under side of each of the guide plates 100—101 which are disposed around the rod so as to bear against three faces thereof. By these means each of the rods is properly centered for free smooth reciprocation through the openings of the guide plates.

While there have been shown and described rods of hexagonal cross sectional form it will be apparent that the invention is not necessarily limited to a rod of this construction but that use may be made of any form of rod where spaced guide rollers may be employed for maintaining the rods properly centered.

The gripper rod 109 carries upon its upper end, at a substantial elevation above the guide plate 100, a head block 113 which carries the two spaced parallel pivot pins 114 which extend in a direction transversely of the machine. Each of these pivot pins has oscillatably supported thereon one of a pair of co-acting jaw members 115, each of which comprises three upstanding fingers 116.

At one end of the head block 113, each of the jaws has connected or attached thereto one of a pair of downwardly extending cam rods 117. These cam rods pass downwardly through the openings 104 of the upper guide plate as shown in Figure 8.

As is clearly shown in Figures 7, 9 and 12 the cam rods 117 have the relatively long outwardly diverging portions *a* which terminate in the oppositely directed high points *b*. From these high points there are the downwardly converging portions *c* which terminate at the oppositely and outwardly directed low points *d*. From these low points *d* the rods 117 again gradually diverge throughout the terminal portions *e*. The spacing between the free ends of the terminal portions *e* is not, however, as great as that between the high points *b*.

Supported from the under side of the top guide plate

100 are the two spaced gripper operating rollers 118 between which the cam rods 117 pass and against each of which the outer side of one rod bears. These rollers 118 are fixed against any movement except rotary movement and accordingly as will be readily seen upon reference to the figures above mentioned, when the head 113 moves up and down the angularly related outer surfaces of the rods 117 will pass over the rollers and effect oscillation of the rods and relative movement of the sandwich gripping jaws 115.

Above the head block 113 the jaws are connected together by springs 119 which constantly tend to swing the jaws together and at the same time maintain the cam rods 117 in firm contact at all times with the opposing rollers 118.

The rod 110 is slidably extended at its upper end through the head block 113 of the gripper as shown in Figure 43 and supports upon its upper end above the head block, the V-shaped elevator cradle 120. This cradle 120 is open at its sides and the length of the cradle extends in the same direction as the length of the opening 107 of the wrapper sheet supporting table, through which the elevator cradle and gripper jaws pass in the operation of removing a sandwich from a basket and extending it upwardly through the table opening 107.

It is believed that it will also be apparent at this point that the gripper jaws and also the elevator cradle move upwardly through the sandwich carrying basket and also that the spaces or passages 92 at the sides of each basket receive the fingers 116 of the gripper jaws so that such jaws may easily slide in across the sides of the sandwich in the basket and move together to secure the sandwich.

Each of the rods 109 and 110 has secured thereto between the guide plates 100 and 101, a yoke 121 and each yoke is connected with a rocker arm 32 by means of a pin 122 which is slidably connected in a slot 123 formed in the end of the arm. Thus it will be seen that the rotation of the cams 24 will effect the up and down movement of the rods 109 and 110 and the contour form of the cams is designed to give the gripper unit and the elevator cradle a prescribed relative movement during their vertical reciprocation.

Receiver, folding and conveying means

The previously referred to horizontal top frame which is generally designated 15 comprises the spaced parallel side rails 124 which extend longitudinally of the machine and the cross connecting front end rail 123 and the transverse rear end rail 126. The transverse rail 126 is secured between the upper ends of the rear end standards 12 of the frame structure and the side rails 124 rest upon the top of this transverse rail 126 as shown in Figure 2 while at the opposite or front end of the machine the horizontal top frame 15 is supported by a vertical standard 127 which is at the left hand side of the frame or opposite from the rotary carriage.

The transverse rear end rail 126 has an upwardly opening V-shaped recess 128 formed therein as is clearly shown in Figure 2 for the purpose hereinafter described.

The rails 124 are preferably of angle formation and positioned with one flange disposed horizontally and directed inwardly toward the longitudinal center of the machine and with the other flange extending upwardly therefrom. By this arrangement means is provided for rotatably supporting the transverse front and rear endless conveyor shafts 129 and 130 respectively.

The shaft 129 extends beyond the outside of the left hand rail 124 and carries on this extended end a sprocket gear 131.

The rear or back end shaft 130 likewise extends through the side rail 124 at the right hand side of the frame and carries a sprocket wheel or gear 132 as shown in Figure 4. This sprocket gear 132 has trained thereover the driving chain 133 which passes downwardly and around the sprocket gear 26 on the counter shaft 21 and upon one side runs across an idler sprocket wheel 134 which is mounted upon the inner side of the adjacent corner post or upright 12 as shown in Figures 4 and 6.

Within the space between the rails 124 the shafts 129 and 130 carry at their ends, the sprocket wheels 135 and the sprocket wheels or gears 135 upon one shaft are connected with those upon the other shaft by the endless chains 136.

Extending transversely of the frame and connecting the sprocket chains 136 are a number of flat bars 137, to

each of which is secured the triangular five pronged pusher 138. As is clearly shown in Figures 2 and 5 particularly such pusher is made up of the spaced flat prongs or fingers 139 which are of graduated length, the central one being of maximum length and the side ones being cut off at their free ends so that the pusher has a triangular form as is clearly shown in Figure 2.

In the operation of the machine the pushers which are at predetermined spaced intervals move in inverted position as shown in Figure 2 with the top runs of the sprocket chains 136 toward the front end of the machine and, as is shown in Figures 7, 9, 12, 15 and 16, the forward or front conveyor shaft is positioned just slightly beyond or in front of the line of vertical movement for the elevator mechanism so that these pushers swing down and start to move back toward the rear of the machine just after they have crossed over the line of vertical movement for the elevator mechanism.

Also secured transversely between the sprocket chains 136 are resiliently supported press plate units 140. Each of these units comprises a flat bar member 141 which is secured at its ends to and between the sprocket chains 136 and the press plate 142 which is in spaced parallel relation with the bar 141 and is connected thereto by the yokes 143 which are substantially U-shaped and are secured at the free ends of the two side portions to the top or back of the press plate as shown in Figure 14 and encircle the supporting bar 141. In addition each press plate carries two bolts 144 which engage at their head ends in the adjacent bar 141 and encircling each of these bolts is an expansion spring 145 which constantly urges movement of the press plate away from the adjacent bar 141.

Each of the press plate units 140, of which there are a number equal to the number of pushers 138, is positioned directly in front of a pusher as is clearly shown in any one of Figures 7, 9, 12, 15 or 16. It will also be seen upon reference to these figures that when the pushers are directed downwardly and are being moved by the chains 136 toward the rear of the machine, the press plate unit in front of the pusher will be arranged to have the press plate with its working face directed downwardly. This working face bears against the portion of the sandwich wrapper which lies across the upturned edge of the sandwich or that edge which represents the base of the triangle which the triangular cut sandwich defines, as hereinafter more fully described.

Extending transversely of the frame 15 and having bearing at its ends in the upstanding flanges of the side rails 124, is a rock shaft 146 which is disposed adjacent to the forward shaft 129 but upon the opposite side of the vertical line of movement of the elevator mechanism 98 from the shaft 129 as is clearly illustrated in any one of Figures 7, 9, 12, 15 and 16.

Secured to the rock shaft 146 is a triangular plate 147 which functions as a gate in the path of movement of the sandwich from the machine as will be hereinafter described. Upon the left hand side of the machine the rock shaft 146 carries the short crank arm 148 and pivotally attached to this arm 148 is an end of a pitman 149, the other end of which is pivotally attached at 150 to the free end of the upwardly extending bell crank lever arm 37.

At the front end of the machine, forwardly of the vertical plane of the front conveyor shaft 129 the side rails 124 have secured to the inwardly extending flanges thereof the short inwardly projecting bracket plates 151.

Extending longitudinally upon opposite sides of the longitudinal center of the machine are the spaced parallel bars 152, each of which is secured at one end to the end rail 125 while at its forward end each one is secured to a bracket plate 151, as is shown in Figure 1. These bars 152 provide supporting means for the hanging bearings 153 which rotatably support the transverse eccentric shaft 154.

Upon the eccentric shaft is supported in the vertical longitudinal and central plane of the machine the folder slide actuating eccentric 155.

The bars 152 also support and are connected by the transversely extending V bridge 156. Secured to this bridge in spaced parallel relation are the two longitudinally extending tracks 157 which are of channel cross section and which are positioned with their channels directed inwardly toward the center of the machine. At their forward ends these tracks 157 are secured to and

support a fixed wall plate 158 which forms one side or wall of a sandwich receiver into which the sandwich is elevated by the mechanism 98. This receiver wall plate 158 has a V-shaped recess 159 formed therein, the downwardly directed apex of the recess being in the vertical, central longitudinal plane of the machine.

The face of the plate 158 has formed thereon the spaced vertical ribs 160 and the spacing between these ribs corresponds to the spacing of the fingers 16 of the sandwich gripping jaws whereby when a sandwich is elevated into the receiver one side will ride against the ribs 160 and the fingers of the adjacent jaw of the gripper will slide in the recesses 161 between the ribs 160.

As is clearly shown in Figures 7, 9, 12, 15 and 16 the bottom edge of the wall plate 158 is curved outwardly or toward the front of the machine, this curved portion being designated 162.

Supported by the tracks 157 for reciprocatory movement is a runner which is generally designated 163. This runner comprises the two spaced parallel side rails 164 which at their rear ends are connected by the integral transverse stretcher 165. At the opposite or forward ends these bars are connected by a detachable or removable stretcher 166 which is secured to the bars 164 by the cap screws 167. Each of the runner bars 164 carries a pair of rollers 168 which are supported for rotation about vertical axes and which bear against the back wall of the channel of a track 157 in which the runner bar is positioned as shown in Figure 17. In addition each of the runner bars carries two rollers 169 which are supported for rotation on horizontal axes directed transversely of the runner and these rollers contact the top and bottom walls of the channel in which the bar is located. Thus it will be seen that the runner is supported both horizontally and vertically for free running movement.

Formed integrally with the rear stretcher 165 of the runner is a substantially V-shaped folder blade 170, the rear end of which is positioned in the V recess 159 through which it has sliding movement in the back and forth movement of the runner. The action of this V-folder blade will be hereinafter described.

The forward stretcher carries an upwardly and rearwardly extending arm 171 upon which is rotatably mounted the eccentric follower roller 172, Figures 1 and 4, which is engaged by the periphery of the eccentric 155.

The runner 163 has attached to its forward end, one end of a pull spring 173 which constantly tends to pull the runner toward the front of the machine in opposition to the rearward thrust movement which is imparted to the runner by the eccentric 155.

Fixed to the bridge 156 at opposite sides of the transverse center thereof or of the low point are the two rearwardly extending arms 174, upon the rear end of each of which is carried the vertical shoe 175. These shoes have their rear faces, which are vertically disposed, in the plane of the rear face of the fixed wall plate 158 so that one side of the sandwich as it is moved upwardly across the rearwardly directed face of the plate 158 will be opposed to or in contact with the rearwardly directed faces of the shoes as is clearly shown in Figure 16.

The arms 174 and the shoes 175 carried thereby are also properly spaced so that the fingers 139 of the pushers will pass between the arms 174.

Secured to the side portions of the bridge 156, forwardly thereof, as indicated at 176 in Figures 7, 9, 15 and 16 are the flat resilient relatively long fingers 177 which extend rearwardly across the path of upward movement of the sandwich by the elevator mechanism. These fingers are engaged and pressed downwardly slightly by the press plates, as shown in Figure 12 to facilitate the maintenance of the wrapping sheet in proper place on the upwardly directed edge of the sandwich as will be hereinafter described.

In spaced relation with the fixed wall plate 158, is another vertically disposed fixed wall plate 178 which, like the plate 158 has a V recess 179 which aligns with the recess 159 of the opposite or front plate 158. This plate 178 also has a bottom edge curved as indicated at 180, away from the curved bottom or lower edge portion 162 of the forward plate. Also the plate 178 which may be referred to as the rear or back plate, has the vertical forward standing ribs 181 which are parallel with the ribs 160 of the forward plate and in line with such ribs longitudinally of the machine. These ribs 181 are

spaced apart to receive the upwardly moving fingers 116 of the adjacent jaw 115 of the sandwich gripper. The space between the plates 158 and 178 is clear and in line with the opening 107 in the underlying wrapper sheet receiving or supporting table 106. This space forms the receiving area or receiver into which the sandwich is elevated and is generally designated 182.

At the bottom of the V recess 179 of the back or rear wall plate 178 there is formed a slot 183 and this is carried rearwardly and upwardly as indicated at 184 in Figure 4 in the right hand side of a V-shaped trough 185, the forward end of which trough is fixed in the V slot 179.

As is shown most clearly in Figures 7, 19, and 16 the top edges of the two sides of the V-trough 185 slope upwardly slightly from the rear wall plate for a short part of the length of the trough. Such upwardly and rearwardly inclined edges, designated 186, then intersect the forward vertical edges 187 of longitudinally extending rectangular openings 188 which are cut down in the sides of the V-trough.

Secured to the rear end of each of the bars 152 is an end of a folder arm 189. This arm, which has its forward attached end at an elevation above the elevation of the top edges 186 of the trough, extends downwardly and rearwardly across the adjacent trough edge 186 and along the outer side of the trough as is clearly shown in Figures 7 and 9 and further extends across a part of the adjacent trough wall opening 188. These arms are turned or twisted toward their rear ends until they present into the trough through the openings 188 the guide faces 190. Each of these guide faces or surfaces extends the length of the opening 188 and joins the opposite end edge thereof from which point the V-trough resumes its unbroken form.

The inner side of the twisting portion of each of the arms 189 is defined by a rib 191 which is in close proximity to the outer side of the wall of the trough and, as is shown in Figure 7, this rib continues through a portion of the length of the guide face 190 where it meets an end of a heater or an electrically heated sealing strip or rib 192 which extends lengthwise of the trough for a part of the length of the guide face 190 as is shown in Figure 7. This sealing rib 192 is in the form of a metal housed electrical resistance element to which electric current is supplied in a suitable manner.

In the use of sheets of cellulose material of well known character for wrapping the sandwiches corner ears 193 of the wrapper material are turned down as such ears pass rearwardly between the top edges 186 of the trough walls and the fold arms 189 and the folded corners move across the sealing rib or heater 192 and are sealed as will be readily apparent upon reference to Figures 21 to 24.

As the sandwich continues to move rearwardly in the trough under the action of a pusher 138 the side edges move across the obliquely positioned heated sealing plates 193, Figure 1, which complete the sealing of overlapped edges of the cellulose wrapping sheet.

The rotation of the eccentric 155 is accomplished through the medium of the sprocket chain 194, Figure 3, which passes around the sprocket gear 131, the idler 195 which is rotatably mounted upon the adjacent side of the frame 15, and the sprocket wheel 196 which is mounted upon the shaft 154 at the left hand end thereof.

Wrapping material feeder and cutter unit

As shown in Figure 6, the wrapping sheet receiving table 106 is of polygonal outline, here shown as being square, which form is preferred. This table has one side positioned adjacent to but at an elevation slightly above the forward edge of the obliquely extending platform 63 with which the said one edge of the table 106 is parallel as is clearly shown in the figure referred to.

Upon the inner end of this platform is supported a short horizontally disposed shaft 198 which is directed oblique to the length of the machine and is parallel with the said edge of the wrapper sheet table 106. Upon the rearward end of this shaft 198 is a sprocket gear 199 which is in driving connection through the medium of the sprocket chain 200, with the gear 68 carried upon the underlying counter shaft 65 as shown in Figures 3 and 41.

Upon the other or forward end of this shaft 198 is secured a short cam 201 which carried at its high point the roller 202.

Removably positioned or mounted upon the platform 63 is the automatic wrapper feeding and cutting mechanism which is generally designated 203, the detail features of which are illustrated particularly in Figures 35 to 41 inclusive.

The wrapper feeding and cutting mechanism 203 consists of a frame having spaced parallel side rails 204 and a cross connecting top plate 205. These side rails at their forward ends have the projecting bottom edge portions 206 which function as runners which slidably engage in track grooves 207 which are formed transversely of the platform 63. By this means the proper placement of the wrapper feeding and cutting mechanism upon the platform is assured. The platform has an opening 205' therein through which a securing bolt, hereinafter described, may be reached.

Secured across the inner or forward end of the frame is a shear plate 208 and supported above this shear plate to extend transversely of the frame and also extending rearwardly therefrom a short distance above the top plate 205, is a shield 209. The forward edge of this shield is spaced slightly above the cutting edge of the shear plate 208 to provide the guide slot 210 through which the wrapping sheet is moved onto the table 106.

At the rear edge of the shield 209 the top plate 205 has a transverse opening 211 formed therein and mounted directly beneath this opening between the side rails 204, is a sheet feed roller 212, to which is attached at that end which is nearest to the cam 201 when the wrapper feeding and cutting mechanism is mounted in working position, a ratchet gear 213. This gear 213 is in driving connection with the sprocket gear 67 through the medium of the sprocket chain 214. Thus it will be seen that when the paper feeding and cutting mechanism is mounted upon the platform 63 and the machine is in operation, the feed roller 212 will be maintained in constant rotation.

The highest point of the feed roller 212 is only slightly above the plane of the top surface of the plate 205 so that the wrapping material in the form of a sheet when moved forwardly over the top of the plate 205 will just contact the top of the feed roller 212 and will be caused to move forwardly thereby through the slot 210 in the manner about to be described.

At the outer end of the wrapper feeding and cutting mechanism the side rails 204 extend a short distance beyond the plate 205 and they have rotatably mounted therebetween the idler roller 214.

Attached to the side rails at the outer or rear ends thereof, as shown in Figures 35 to 37 inclusive, are the upwardly and rearwardly inclined arms 215.

The arms 215 are inclined as illustrated in Figures 36 and 37 and are provided to have placed thereacross a shaft 216, carrying a roll 217 of wrapping material such, for example, as the commonly employed transparent cellulose material known as cellophane. By reason of the inclination of the arms 215 it will be seen that the roll of wrapping material will be caused to constantly press against the idler roll 214 and the sheet of material when unwound from the under side of the roll will pass up across the idler roll 214 and then be extended forwardly across the top surface of the plate 205 over the driven feed roll 212 and forwardly through the guide slot 210. By this means the weight of the wrapper roll itself will constantly maintain a drag on the sheet so that the sheet will be maintained flat across the plate 205 and can be discharged in such flat condition onto the table 106.

Slightly forwardly of the feeding roll 212 there are positioned upon the tops of the side rails 204, the upstanding ears 218, each of which is apertured as shown in Figure 40 to receive a pivot or trunnion screw 219.

Disposed above the feeding roll 212 and the adjacent forward end of the mechanism frame is a rock plate 220 having the depending end flanges 221 each of which positions against the inner side of an ear 218 and has a pivot screw 219 secured thereto as shown in Figure 40. By this means the rock plate 220 is supported for oscillation or rocking movement.

The forward edge of the rock plate 220 carries two pairs of spaced pivot knuckles 221'. Each pair of knuckles is positioned to one side of the longitudinal center of the mechanism frame and each pair of knuckles has extending therethrough a pintle 222 which, by reason of the fact that the outer knuckle 221' of each pair is set a slight distance forwardly of the inner one, is disposed slightly obliquely to the longitudinal center of the frame.

Thus it will be seen that the two pintles 222, as shown in Figure 35, converge slightly.

Oscillatably supported upon each pinte 222, is a cutting blade 223 which carries at its top edge two hinge knuckles 224, each of which is positioned against a side of a knuckle 221 to have the adjacent pinte pass therethrough. As will be seen upon reference to Figure 38 the cutting blade supporting pintles 222 are also inclined downwardly and outwardly from the longitudinal center of the frame whereby the edges of the blades are similarly inclined.

The cutting edges of the blades 223 bear against upstanding guide rests 208 carried at the ends of the plate 208 as shown in Figures 36, 37 and 39 and accordingly it will be seen from the description just given of the mounting for the blades that when the plate 220 is rocked to have the forward edge swing down, the cutting edges of the blades will slide down across the slot 210 and shear off against the edge of the shear plate 208, the portion of the wrapping material sheet which may have been projected through the guide slot 210. It will also be seen that in addition to the fact that the blades have a slight rocking movement on the pintles 222, whereby the edges of the blades maintain proper working relation with the edge of the shear plate, the sheet will be cut from the opposite side edges inwardly toward the center which action centers the paper for the next delivery as the paper tends to float when it is released after being cut.

As previously stated the pivots 219 for the rock plate are set slightly forwardly of the pivotal axis for the feeding roll 212. Just rearwardly of these pivots 219 and supported directly above the feeding roll 212 by and for rotation between the side flanges 221 of the rock plate is a free moving idler roller 225.

Disposed beneath the plate 220 and resting upon the top of the shield plate 209 on the front side of the pivotal axis for plate 220 from roller 225, is a spring 226 which constantly urges rocking of the plate 220 in a direction to raise the knives and bring the idler roller 225 into contact with the driven feed roller 212. This rocking movement of the plate 220 is restrained, however, in the manner about to be described, during any period in the operation of the machine when a sandwich is not advanced beyond a predetermined position by the rotating carriage structure.

In addition to the spring 226, each of the pintles 222 carries a spring 227, an end of which bears against the adjacent edge of the plate 220 while the opposite end bears against the top edge of the cutting blade and constantly tends to oscillate the blade in a direction to move the cutting edge thereof into contact with the guide rests 208.

Mounted to one side of the wrapper feeding and cutting mechanism upon a suitable supporting plate 228 is an electro-magnet 229 which is provided with a movable core or armature 230. The magnet is set so that the armature moves horizontally toward and away from the adjacent side rail 204 of the mechanism.

At its outer end the armature 230 carries the upstanding post 231 on the top of which is a rubber head or bumper 232.

Secured to the top of the magnet as indicated at 233 is an end of a leaf spring 234 which extends upwardly and forwardly above the armature and terminates in the downwardly extending leg portion 235. This resilient leg of the spring 234 is positioned directly behind the armature carrying post 231 so that when the electro-magnet is energized and the armature is drawn back away from the adjacent rail 204 of the mechanism frame the post will bend the spring leg and place the spring under tension. When the magnet is de-energized the reaction of the spring will then cause the armature to be thrust forwardly again to its former position.

Coupled with the rock plate 220 in a suitable manner and at the side of the mechanism frame adjacent to the electro-magnet, is an end of a latch arm 236. Adjacent to its other end the arm carries the outwardly projecting cam ear 237. The means here shown for coupling the arm with plate 220, comprises a bar 238 which is secured across the tops of the flanges 218 of the rock plate and has one end projecting beyond a flange to have the end of the arm secured thereto as shown in Figure 35. The arm 236 extends rearwardly from the rock plate a substantial distance beyond the rollers 212—225 and its free rear end is adjacent to the side of the armature post 231 opposite from the spring leg 235. With this arrangement, when the arm 236 has its free end

forced upwardly by engagement of cam roller 202 with the underside of the ear 237, whereby to effect the oscillation or rocking of the plate 220 and the downward cutting movement of the knife or knives, the spring 5 will kick the armature forward so that the post 231 will be positioned beneath the free end of the arm 236 thus holding the knives in the down position and maintaining the idler roller 225 elevated from contact with the wrapper feeding roller 212. When the electro-magnet is energized and the armature is retracted as illustrated in Figures 35 to 37 the post 231 will be pulled out from beneath the free end of the arm 236 and the spring 226 will then exert its effect to oscillate the plate 220, raising the knives and lowering the roller 225 toward the roller 212. If a sheet of wrapping material is lying over the roller 212 as shown in Figure 39, it will be seen that the sheet will be then gripped between the two rollers and since the roller 212 is constantly rotating the sheet will be fed forwardly through the slot 210. When the plate 220 is again rocked to lift the roller 225 the wrapper feed will cease, the knives will be lowered to shear off the sheet and the arm supporting post will be kicked forwardly by the spring to position under the free end of the arm and thus maintain the parts in this position until 25 the magnet is again energized.

The raising of the free end of the arm 236 from the position in which it is illustrated in Figures 37 and 39, is effected by the constantly rotating cam 201. When the wrapper feeding and cutting mechanism is placed in 30 position upon the platform 63 the laterally extending cam ear 237 carried by the arm 236 comes into position directly above the cam 201 as is clearly shown in Figure 6 and with each revolution of the cam, the roller upon the high point of the cam rides under this ear and elevates the free end of the arm to rock the rock plate 35 in the manner described if the arm is not already being maintained in raised position by the upstanding post 231 of the magnet armature.

Directly beneath the opening 205' the plate 228 has a 40 slot 242 therein which lies on and is directed lengthwise of the longitudinal center of the plate 205. When the paper feed unit is in position on the platform 63, the plate 228, and particularly the slot 242 lies over the adjacent top one of the side rails 13 and, as shown in 45 Figure 6, a bolt 242' extends down through the slot 242 into the underlying rail 13 and secures the unit in position.

By the provision of the elongated slot 242 the paper feeding and cutting unit may be shifted nearer to or 50 away from the sheet receiving table 106 for the purpose of lengthening or shortening the cut wrapping sheet 240, deposited on the table over the opening 107. This is brought about by reason of the fact that in so shifting the unit the cam ear 237 is moved with respect to the 55 actuating cam 201 in that the period of engagement of the cam roller 202 with the ear 237 is decreased after forward positioning of the unit, providing for a longer wrapper sheet and vice versa. At the same time the cut sheet will always be exactly centered on the table over opening 107, whether the sheet be lengthened or shortened.

The electro-magnet 229 is connected in a suitable 60 electric circuit, not shown, which is controlled, as regards the opening and closing thereof, by a switch unit 65 238, see Figures 3, 4 and 5, which unit includes a relatively long curving actuating finger 239 which stands up in the path of movement of the baskets carried by the rotating carriage but is so positioned that it will pass between the spaced wall strips 91 of each basket. However, if the basket is carrying a sandwich, the sandwich will bridge the space between the strips 91 and will ride over the curved finger 239 depressing it and closing the switch 238, thereby closing the circuit in which the electro-magnet is connected and energizing the magnet. This then effects the described actions with regard to the 75 wrapper feeding and cutting mechanism whereby a sheet of the wrapper, of proper size, is projected onto the table 106 to overlie or cover the opening 107 through which the sandwich is elevated. Such sheet is shown in a number of views as, for example, in Figures 7, 9, 12, 13, 15 and 16 where it is designated 240.

In the operation of the machine, when the driving motor 17 has been set in motion rotary power will be transmitted through the speed reduction mechanism 18 80 85 by way of the sprocket chain 23 to the counter shaft

21. In addition to rotating the cams 24 to effect the necessary rocking motion of the rocker arms 32 and the rotation of the cam 25 to effect the rocking of the bell crank lever arm 37, rotary power will be transmitted to the unit 42 to rotate the shaft 47. The rotation of the shaft effects the corresponding turning or rotation of the crank arm 53 and the adjacent head 51 and with each revolution of the crank arm the roller 54 will enter a crank slot 85 formed in the rotary carriage plate or crank plate 80 and impart one rotational step to the carriage. As soon as the carriage has moved the one step the crank roller 54 leaves the slot 85 and the rotary head 51 has moved into position in a semi-circular recess 82 of the lock plate 81 and will remain in such recess to hold the carriage against further rotary movement until the crank comes around and the roller 54 enters the next slot 85. This will, of course, turn the head 51 to the position where the next approaching or progressing point 83 and the head recess 52 are in position for the point to enter the recess whereupon the next step of the carriage will take place.

At the completion of each step of the rotary carriage a basket 86 will be disposed directly below the opening 107 of the wrapper sheet table 106 as shown in Figure 7, ready to have a sandwich removed therefrom and elevated into the receiver.

During this intermittent or step by step rotation of the carriage, rotary power will be transmitted from the shaft 47 by way of the sprocket chain 71 to the outer shaft 65. This shaft is in continuous rotation and from this shaft are driven continuously the roller 212 of the wrapper cutting and delivering unit and the cam 201.

The sandwiches cut in a triangular form are placed, as previously stated, in the baskets 86 of the rotary carriage with the point of the triangle down, thus placing the flat base portion of the edge of the sandwich upwardly and substantially horizontally. As the sandwich moves around, just before the carrying basket comes into position below the opening 107 of the sheet supporting plate the sandwich passes over, contacts and depresses the switch finger 239. In doing this the switch is closed and an electric circuit, not shown, in which the electro-magnet 229 is connected, is closed to energize the magnet and to effect the retraction of the magnet armature 230. As previously stated this armature is retracted against the resistance of the flexible finger 235 and when so retracted the post 231 will be pulled from beneath the arm 236 allowing the spring 226 to thus upwardly against and oscillate the rock plate 220. This will bring the idler roller 225 down against the top of the end of the wrapper sheet which is lying over the constantly rotating roller 212, pressing the wrapper sheet against the latter roller and causing the sheet to be moved forwardly through the slot 210. Simultaneously with the lowering of the roller 225 the cutter blades 223 will be raised so as not to interfere with the ejection of the end of the wrapper.

As soon as the proper amount of the wrapper sheet has been projected through the slot 210 the cam, which is in constant rotary motion, brings its high point around against the under side of the latch arm ear 237 and thrusts the free end of the latch arm 236 upwardly. When this occurs several actions take place simultaneously. First, the idler roller 225 rises and the knife 223 moves downwardly; second, the forward movement of the wrapper sheet stops and the descending knife shears off the portion of the sheet which has been extended through the slot 210; third, as soon as the shearing action is complete the arm 236 will be in a position where the tensioned spring finger 235 can kick the armature out and re-position the post 231 below the end of the arm 236 so that as the high point of the cam moves out from under the latch arm ear 237 the post 231 will be in position to prevent the spring 226 oscillating the plate and lowering the arm 236. The arm thus stays in this raised position and the knife 223 remains down with the idler roller 225 out of contact with the constantly driven roller 212 until the electro-magnet is again energized by the closing of the switch 238 as a result of the actuation of the switch finger by a sandwich moving across it in the next succeeding basket of the sandwich carriage.

The foregoing actions take place between the time the sandwich contacts the switch finger 239 and the time the sandwich carrying basket comes into position below the opening 107 of the wrapper sheet table. The cut

wrapper sheet is therefore resting flat upon the top of the table over the opening 107 and since the wrapper sheet is approximately of the same configuration as the table it will be seen, upon reference to Figure 6, that the longitudinal center of the opening 107 will be in line with diagonally positioned corners of the wrapper sheet and consequently when the triangular cut sandwich is elevated against the under side of the wrapper sheet through the opening 107 the opposite ends of the upwardly facing bottom edge of the triangular sandwich will also be directed toward and located between the diagonally positioned corners of the wrapper sheet and the other diagonally positioned corners of the wrapper sheet, when folded down against the adjacent sides of the sandwich will extend down across the downwardly directed point of the sandwich.

When the sandwich has come into the position shown in Figure 7 and the cut wrapper sheet has taken its position on the perforated table 106 the folder blade 170 will be in fully retracted position so that the sandwich may be freely elevated into the receiver between the plates 153 and 178. Also the press plate 140 and the following pusher 138 will be swinging down and around to advance toward the receiver as shown in Figure 7. The elevator 98 will be fully lowered but will immediately begin to move upwardly under the action of the rocker arms 32, which arms function independently, one moving the elevator cradle 120 which receives the downwardly directed point of the sandwich in its V and the other rocker arm moving the sandwich gripper, the jaws of which are at this time fully separated or spread apart.

As shown in Figure 7 the cam rods are at their lowermost positions where the camming rollers 118 engage the high points of the rods, thereby forcing the lower ends of the rods inwardly and separating the jaws to the fullest extent.

As the rocker arms 32 begin to rise the V-cradle 120 is elevated into position under the sandwich and the cam rods 117 will move up between the rollers 118, the rollers immediately riding onto the inwardly converging portions c of the rods thereby permitting the spring 119 to draw the jaws 115 together, during which time the jaws have entered or are entering the sandwich basket from the bottom, the fingers of the jaws passing between the vertical wall strip portions 91 of the basket. The elevator structure continues to move upwardly through the basket during this closing action of the jaws on the sandwich, such closing action continuing until the cam rollers 118 reach the points d on the cam rods, at which time the jaws will be closed to the fullest extent under the action of the spring 119.

During such upward movement of the elevator with the sandwich, the sandwich will have passed through the opening 107 of the table 106 and will pick up the wrapper sheet, carrying it upwardly with the sandwich as shown in Figure 9. As the camming rollers 118 begin to leave the low points d a very gradual pressing together of the lower end portions e of the cam rods begins to take place to permit a gradual opening of the jaws for relaxation of the gripping action of the same on the sandwich. At this time a part only of the sandwich has been elevated above the table.

As seen in Figure 9 the sandwich eventually reaches the position where it is lightly squeezed between the opposing faces of the wall plates 153 and 178 of the receiver 182, the oppositely curved lower edge portions of such walls guiding the wrapping sheet 240 down across the opposite sides of the sandwich. At this point the cam rods 117 have moved to a position where the rollers 118 are approaching the free ends of the rods and also, as shown in Figure 9, the pusher plate 138 is beginning to move rearwardly toward the front side of the receiver, the press plate 142 has already reached its horizontal position in its movement and is beginning to move over the upper part of the receiver and the gate plate 147, operated by the bell crank arm 37, is swinging downwardly into the V-trough and forwardly toward the rear side of the receiver for cooperative action with the V-folder 170.

As the sandwich is moved up between the opposing plates 153-178 the fingers of the grippers enter the channels in the faces of these plates and the wrapper is drawn across the plates and the frictional contact drags the wrapper tightly across the top of the sandwich.

The upward movement of the grippers is slackened

with respect to the elevator cradle and remain stationary for a period while the sandwich is moved up by the elevator 120 until the sandwich finally reaches the uppermost limit of its movement as shown in Figure 12. By this means the lower part of the sandwich is held in proper position and the top part is received and held between the receiver plates, thus giving the sandwich proper support top and bottom and preventing it from tilting. At this time, the gate 147 is pressing against the rear side of the sandwich to hold the wrapper tightly thereagainst and the top of the sandwich has come into contact with the fingers 177 which, while mounted for up and down swinging movement, are contacted and resiliently or yieldingly pressed downwardly by the press plate 142 which is moving in advance of the pusher 138.

As soon as the sandwich reaches this position the eccentric 155 advances the V-folder blade 170 slightly to engage beneath and support the sandwich and wrapper as illustrated in Figure 13, while the sandwich supporting cradle 120 is being withdrawn or lowered. And immediately following this preliminary movement of the folder and the substantially simultaneous downward movement of the elevator cradle, the eccentric 155 acts further to complete the shifting of the V-folder plate 170 so as to fold in under the sloping or downwardly converging edges of the sandwich the adjacent triangular side of the wrapper, as shown in Figure 15.

Also shown in Figure 15 is the position of the pusher against the forward side or face of the sandwich and the position of the gate 147 against the opposite side, holding the sandwich against rearward movement while the folder plate 170 is functioning. However, the gate 147 and pusher 138 are synchronized so that immediately upon the completion of the first fold by the V-plate 170 the gate will swing back as the sandwich is moved back by the pusher and the sandwich is therefore moved rearwardly, as shown in Figure 16, across the receiver and off of the folder plate 170 into the V-trough 185.

In order that too much pressure may not accidentally be applied to the rearward side of the sandwich by the gate plate 147 the pitman 149 which rocks the shaft 146 upon which the plate 147 is carried, is provided with a yieldable spring coupling 149a which is lightly tensioned so that when the proper amount of resistance is offered by the sandwich body to the further swinging of the plate 147 thereagainst the said spring coupling will yield to allow the bell crank arm 37 to have the necessary additional movement required by the operation of the cam 25, without damaging the sandwich.

When the V-folder plate 170 folds under the forward triangular side of the wrapper the downwardly directed point of the wrapper will be crumpled in the angle at the bottom of the folder and when the pusher 138 moves the sandwich from the folder into the V-trough the converging side walls of the trough will fold in the other triangular portion of the wrapper across the converging side edges of the sandwich body and over the previously folded in angle of the wrapper. The downwardly directed point of the triangular side of the wrapper which is folded by the side walls of the V-trough will be gathered as a tail 240a in the rearwardly extending and upwardly curving slot 184 in the right hand side of the V-trough and as the sandwich body moves rearwardly in the V-trough this slot will turn up the gathered point or tail of the wrapper against the adjacent side edge of the sandwich body where such point will be sealed against the adjacent part of the wrapper and the overlapping portions of the wrapper extending along each of the convergent side edges of the sandwich body will be sealed together as the sandwich moves rearwardly in the trough across the heated sealing plates 193.

It will be readily apparent that after the two triangular side portions of the wrapper have been folded across the convergent side edges of the sandwich as illustrated in Figure 16 there will be formed at each end of the top edge of the sandwich the outwardly extending substantially triangular ear 240b which, as shown in Figure 21, will extend across the top edge of the adjacent side wall of the V-shaped trough 185. These oppositely directed ear portions 240b of the wrapper will lie beneath the fold arms 189 and as the sandwich body moves toward the rear of the V-trough they will pass between the converging wall edges 186 and the arms 189 and be bent down and folded under as shown in Figure 22. The rib 191

upon which the folded under ear piece 240b rides, gradually drops below the top edge of the trough and, as previously stated, and as is shown in Figure 9, runs into or joins the end of the sealing rib 192 which, as previously stated, is heated. This heated sealing rib bears across the adjacent side edge of the sandwich body below the top corner and causes the cellulose wrapping material, which is thermo-plastic, to be softened and to seal itself to the underlying layer of material.

10 While the heated sealing rib 192 has been illustrated in Figure 24 as being in the form of a long relatively narrow body which projects, as a rib, beyond the face 190, it is within the purview of the present invention to provide means for directly heating the guide face 190 15 so as to seal a relatively long strip across the under edge of the sandwich at each side.

By this method of strip sealing a portion of the downturned flap or ear piece 240b against the body of the wrapper, the maintenance of the downturned flap or ear piece against the side of the wrapper is assured when such side piece passes the cut out area or space 188 and rides onto or against the inner face of the trough wall. After the ear pieces or flaps are thus secured they will not be damaged or pulled back but will ride against the inner faces of the trough wall and be carried over the previously referred to heated sealing plates 193 which will apply the necessary heat from the top to the bottom of the adjacent side edge of the sandwich so as to tightly seal all contacting overlying surfaces of the wrapper material.

20 30 In order to insure this complete sealing of the wrapper, the sealing plates 193 converge downwardly and rearwardly and also are of slightly arcuate transverse form so as to follow any longitudinal curvature in the crust 25 of the sandwich bread which is sometimes found when 35 the crust has dried out slightly.

As will be readily obvious from the showing of the drawings and the preceding description, as soon as the elevator mechanism has been lowered from within the basket from which the sandwich has been removed, the star or Geneva wheel mechanism which imparts the necessary step by step rotation to the carriage structure will function to engage in a crank slot 85 while at the same time releasing the carriage by the rotation of the head 51 to the proper position to receive the next point 83. This 40 will bring the next sandwich carrying basket into position to be elevated and wrapped in the manner described.

In this machine the individually wrapped sandwiches are moved from the wrapping station through the V-trough in spaced relation, by the pushers 138 as illustrated particularly in Figure 12. Thus there is no pushing of one sandwich against the other which might cause damage to a sandwich particularly in a machine where a 50 long row might be moving from the wrapping station 55 to the point where the sandwiches are removed or discharged from the machine.

While, of course, it will be obvious that a machine of this character may be set or adjusted to operate at varying speeds, an actual working embodiment of the invention 60 has been operated and satisfactorily wrapped triangular cut sandwiches having different types of fillings and accordingly having different thicknesses, at a rate of approximately fifty sandwiches per minute or three thousand per hour.

65 It has been demonstrated also that a machine of the character herein described will envelop the sandwiches in an air-tight wrapper which will keep the sandwich in a satisfactory condition for as long as a week or ten days.

70 It is also an accomplishment of the present invention to wrap sandwiches of the softest material without the employment of any type of stiffening or backing around the edges thereof due to the novel coaction between the grippers which hold the sandwich together and in proper 75 position while it is being elevated into the receiver and to the novel means of holding the sandwich in the receiver while the second wrapping step is being carried out by the V-shaped folder plate 170.

I claim:

80 1. A machine for wrapping triangular cut bodies such as sandwiches, comprising a carriage for delivering triangular cut bodies to a predetermined station in "on edge" position with the apex of the triangle directed downwardly, means for supporting a wrapper sheet horizontally over the said station, means for elevating the

body in said position from the carriage against the wrapper sheet, a receiver disposed above the wrapper sheet supporting means and into which the body and wrapper sheet are introduced, said receiver comprising spaced plates between which the body and wrapper slide, the plates functioning to smooth down opposite portions of the wrapper against opposite sides of the body, said receiver plates having opposite aligned V recesses between which the body and wrapper are brought to rest, a V-shaped means movable through one recess across the receiver and beneath the body to fold under a part of one portion of the wrapper sheet, means for then moving the body through the other recess, the bottom edge of the said other opening functioning to fold under a part of the other portion of the wrapper in overlapping relation with the first folded part, and means for sealing together the overlapping parts of the wrapper.

2. A wrapping machine structure of the character stated in claim 1 with means for grasping opposite sides of the body and wrapper during the period of transfer from the carriage into the receiver.

3. A wrapping machine of the character stated in claim 1 with a movable gate adapted to position in the said other recess, and means for removably maintaining the gate in the said other recess against the adjacent side of the body to maintain the body in position while the said movable V-shaped means is functioning to fold under the part of the said one portion of the wrapper sheet.

4. A machine for wrapping bodies made up of separable portions, comprising a movable carriage for delivering such bodies successively to a predetermined station, a wrapper sheet supporting table having an opening lying in a plane above and in line with said station, a vertically movable elevator mechanism constructed and arranged to grasp the body to hold the portions thereof together and to remove the body from the carriage and move it through said table opening while maintaining the grasp thereon, the body in passing through said opening picking up the wrapper sheet previously deposited thereon on the table, a pair of spaced opposed plate members above the table between which the grasped body and sheet are moved, said members functioning to smooth down opposite parts of the sheet across opposite sides of the body, means for releasing the grasped body and removing the elevator mechanism, means for folding portions of the wrapper sheet in overlapping relation beneath the body, means for sealing the overlapping wrapper portions, each of said spaced plate members having an opening conforming to the contour of the body, the body and sheet being positioned by the elevator mechanism between said openings, the said folding means comprising a member movable through one opening beneath the body and across the space between the plate members to fold under one of said portions of the wrapper, and means for moving the body through the other one of the plate member openings, the edge of the said other one of the openings functioning as a means for folding under the other one of the said portions of the wrapper.

5. A machine for wrapping bodies comprised of flat separable portions, such as a sandwich, comprising a movable carriage for delivering such bodies successively to a predetermined station with an edge horizontal and facing upwardly, a wrapper sheet supporting table having an opening lying in a plane above and in line with said station and upon which table a wrapper sheet is located over the opening, a vertically movable elevator adapted to remove the body from the carriage and move it upwardly through the table opening, said elevator mechanism including means for grasping the body from opposite sides to hold the portions together, the body in passing through said opening picking up the wrapper sheet, a pair of spaced opposed members above the table between which the elevator positions the body and wrapper, said members functioning upon movement of the body between them to smooth down opposite parts of the sheet across opposite sides of the body, means for retaining the body and wrapper in position between said members while the grasping means is released and elevator is removed, a folding member movable transversely of the underside of the body to fold under one of the said portions of the wrapper, one of the said spaced members having an opening, means for moving the body and wrapper through said opening after the functioning of the folding member, an edge of the said opening function-

ing as a second folder to fold under the other one of the said portions of the wrapper, and means for sealing together the folded portions of the wrapper.

6. A machine for wrapping triangular cut sandwich bodies, comprising a wrapper sheet supporting tables having an opening of a size to permit the passage of the sandwich therethrough, means for locating a sandwich in position beneath said opening with the point of the triangular sandwich body directed downwardly, an elevator mechanism having a substantially V-shaped cradle, means supporting the elevator cradle for movement upwardly from beneath the sandwich body and in the direction of the table opening to pick up the sandwich body and carry it upwardly through said opening, the body lifting a wrapping sheet from the table in its passage through the opening, means forming a part of said mechanism moving in cooperation with the cradle for grasping the sandwich body from opposite sides to maintain the parts of the body against separation, a pair of spaced members disposed above the table with the space between them in line with said opening, the spacing of said members being approximately equal to the thickness of the sandwich being elevated, said elevator cradle and cooperating means moving the sandwich body and the wrapper upwardly between said spaced members whereby the members function to smooth down the wrapper sheet across the opposite sides of the body, one of the said spaced members having a V-shaped opening generally conforming to the triangular form of the sandwich body and in front of which the sandwich body and wrapper are brought to rest by the elevator mechanism, means for retaining the sandwich and sheet in a second station position after passing between the spaced members, means for effecting the retraction of the said cooperating means in advance of the engagement of the said retaining means with the sandwich, means for retracting the elevator cradle, means for folding in the wrapper from opposite sides across the underside of the sandwich, said last named means comprising a V-shaped holding member movable across the space between the spaced members from the opposite side of the sandwich from said V-shaped opening, means for moving the sandwich through the V-shaped opening, the edges of such opening functioning as a second holding means to fold portions of the adjacent side of the wrapper into overlapping relation with the portion of the wrapper previously folded under by the V-shaped holding member, the said opposite sides of the wrapper being overlapped, and means for sealing the overlapping portions of the wrapper.

7. A machine of the character described in claim 6, wherein the said means cooperating with the elevator cradle comprises a pair of relatively movable jaws each consisting of a number of upwardly pointing fingers, and the said spaced members having their opposing faces provided with vertical recesses in which said fingers position in their upward movement, the wrapper sheet overlying the opposite sides of the sandwich body bearing against the portions of the said spaced members lying between said recesses.

8. In a machine for wrapping bodies of a triangular form such as triangular cut sandwiches, a carriage structure having a plurality of baskets formed to receive the body with the point of the triangle downward, means for moving the carriage to successively bring the baskets to a predetermined station, means for horizontally supporting a wrapper sheet above said station, a vertically movable elevator mechanism supported beneath said station, said baskets being open top and bottom and said elevator mechanism being of a size to move therethrough, means for moving the elevator mechanism upwardly through each basket when the basket is brought to said station to pick up a body from the basket and move it upwardly against the underside of the wrapper sheet, a pair of spaced members arranged to have the body and sheet moved between and in contact with them whereby to smooth the wrapper down across opposite sides of the body, means for engaging the body and wrapper from opposite sides to hold the wrapper tightly in position, means for retracting the elevator through the basket, means for folding the wrapper first from one side of the body and then from the other side across the downwardly converging undersides of the body, and means for sealing together the folded parts of the wrapper, said elevator mechanism including co-acting grasping jaws movable with the elevator through

the basket for holding the sandwich body from opposite sides to maintain the parts of the body against separation as the body is transferred from its position in the basket to its position between the plates, and means for withdrawing the grasping jaws as the sandwich body arrives at a predetermined position between said spaced members.

9. A machine of the character described in claim 8, with means for pressing down upon the uppermost part of the sandwich body and the wrapper sheet lying thereacross as the wrapper sheet is folded in across the said downwardly converging undersides of the body.

10. In a machine for wrapping bodies of triangular form such as triangular cut sandwiches and in combination, a carriage structure having a plurality of baskets formed to receive such body with the point of the triangle downward and open top and bottom, means for intermittently moving the carriage to successively bring the baskets to a predetermined station, means for horizontally supporting a wrapper sheet above said station, a vertically movable elevator mechanism supported beneath said station and including a sandwich receiving cradle and relatively movable sandwich grasping jaws, means for raising and lowering said mechanism and for imparting concerted and independent relative movement to the cradle and jaws, the cradle having opposite open sides and positioned between the said relatively movable jaws with its open sides facing the jaws, the cradle and jaws being movable as a unit through the baskets, camming means for moving the jaws together to grasp a sandwich body as the cradle and element move into and lift the body from the basket, the elevator mechanism moving the body upwardly against the underside of and picking up said wrapper sheet on the body, spaced members between which the sandwich body and sheet are moved and functioning to fold down the sheet across opposite sides of the body, said camming means functioning to relax the grasp of the jaws and the raising and lowering means slackening the upward movement of the jaws as the body reaches a predetermined position between said members, means for holding the body in the space between the members, the raising and lowering means lowering the cradle and the grasping jaws back through the basket following the holding of the body between the members, and elements operating synchronously to fold the wrapper across the undersides of the body and to seal the wrapper.

11. A mechanism of the character stated in claim 10, wherein the said jaws each comprises spaced fingers pointing upwardly and said baskets are provided at opposite sides with spaces in which the jaw fingers enter in their movement upwardly across the opposite sides of the sandwich body.

12. A machine of the character described in claim 10, in which said jaws comprise a plurality of upwardly pointing spaced fingers, the said baskets having opposite sides provided with spaces for the reception of the jaw fingers in the upward movement of the jaws across the opposite sides of the sandwich body and the said members between which the sandwich body and sheet are moved comprises spaced plates having upwardly extending channels in their opposing faces in which the fingers of the jaws are received and whereby the relaxing separatory movement of the jaws is facilitated.

13. A machine for wrapping bodies of triangular form such as triangular cut sandwiches comprising a table having a quadrangular opening therein for the support of a flat wrapper sheet in position to cover the opening, a relatively long upwardly opening trough of substantially V form disposed in a plane above said table and having one end above and parallelling one side of said opening, the said end of the trough being open, a vertical plate extending down from the said open end of the trough and bordering the end edges thereof, a second vertical plate in spaced relation with the first plate and positioned above and parallelling the opposite side of the table opening, the second plate having a V opening aligned with the adjacent open end of the trough, guide shoes in the opening of the second plate, means for elevating a sandwich through the table opening and to a position between said plates in line with the said end of the trough, the plates functioning to fold down across opposite sides of the sandwich opposite portions of the wrapper sheet picked up by the sandwich in passing through the table opening, a folder element supported for movement through the opening of the second plate into the space between the plates, a gate movable into

the open end of the trough for coaction with said shoes to hold the sandwich body while said folder element is functioning, means movable between the shoes to move the sandwich and wrapper sheet into the open end of the

5 trough, means for moving the gate out of the trough in timed relation to the movement of said body moving means, the said end edges of the trough functioning as a second wrapper folder element as the body and wrapper are moved thereacross, and means for sealing 10 together overlapping parts of the wrapper.

14. A machine of the character described in claim 13, in which the said means for moving the sandwich and wrapper into the open end of the trough is supported for movement lengthwise of the trough to effect continued movement of the sandwich toward the opposite end thereof, and means extending along opposite longitudinal edges of the trough for folding down against convergent undersides of the sandwich body outwardly projecting portions of the wrapper sheet.

15. A machine of the character stated in claim 13, in which said guide shoes are in the form of vertically positioned plates each having one side face substantially parallelling the body engaging face of the second plate and the said means for moving the sandwich and wrapper 20 into the open end of the trough comprises a plurality of spaced parallel members movable between the shoes across the space between said vertical plates toward the open end of the trough.

16. A machine of the character described in claim 13, 30 in which the said folder element is in the form of a V-member substantially corresponding to the V-form of the trough, a carriage for said folder element mounted for reciprocatory movement relative to the shoes and the space between said vertical plates, the folder element 35 passing beneath the shoes, and means for effecting rectilinear movement of said carriage and folder element.

17. A machine of the character described in claim 13, 40 in which the said folder element is in the form of a V-member substantially corresponding to the V-form of the trough, a carriage for said folder element mounted for reciprocatory movement relative to the shoes and the space between said vertical plates, the folder element 45 passing beneath the shoes, and means for effecting rectilinear movement of said carriage and folder element, comprising a rotary cam for causing movement of the carriage and folder element for a folder wrapping operation and spring means for retracting the carriage, said cam being designed to effect a slight preliminary advance movement of the folder element after the sandwich body 50 and wrapper have been elevated to maximum position to hold the body and wrapper while the elevating means is withdrawn.

18. A machine of the character described in claim 13, 55 in which the said sealing means is in the form of heating units disposed at opposite sides of the V trough.

19. In a machine for wrapping bodies of triangular form such as triangular cut sandwiches, means for supporting a wrapper sheet of quadrangular material, means for elevating the triangular body with the base side of the triangle uppermost against the underside of said 60 sheet with diagonal corners of the sheet lying in a line passing centrally lengthwise of the said base portion of the body, spaced folding guides between which the body and sheet lying thereover are moved whereby the opposite diagonal corners of the wrapper sheet will be smoothed down across opposite side faces of the body and the said opposite diagonal corners of the wrapper sheet directed downwardly adjacent to the downwardly directed point of the triangular body, means for supporting the body 65 and sheet in the space between said plates, a V-shaped folder supported for movement beneath the supported body and sheet from one side of the body whereby to fold in edge portions of one side of the wrapper across the converging undersides of the body, means for folding 70 in the edge portions of the opposite side of the wrapper sheet across the previously folded portions of the sheet, the said folding in of the edge portions of the wrapper sheet forming outwardly projecting wrapper sheet ears at opposite ends of the base portion of the body, means for folding down said outwardly projecting ears against the adjacent undersides of the body, and means for sealing the overlapped portions of the wrapper sheet 75 and the down folded ears.

20. A machine for wrapping bodies of triangular form 80 such as triangular cut sandwiches, comprising a table having a rectangular opening therein for the flat support

of a quadrangular wrapper sheet in position over the opening with diagonal corners of the sheet on a line running centrally lengthwise of the opening, a relatively long upwardly opening trough of substantially V form disposed in a plane above said table and having one end open and above and parallelling one long side of said table opening, a vertical plate extending down from and bordering the edges of said open end of the trough, a second vertical plate in spaced relation with the first plate and parallelling the opposite long side of the table opening, the second plate having a V opening aligned with the adjacent open end of the trough, a vertical guide in the opening of the second plate, means for elevating a triangular body base upward through said table opening to a position between said plates in line with the said end of the trough, the body in moving upwardly through the opening picking up said wrapper sheet with diagonal corners of the sheet lying in a line running centrally lengthwise of the base of the body, the plates functioning to fold down across opposite sides of the triangular body, opposite portions of the wrapper sheet whereby the other diagonally positioned corners of the wrapper sheet are pointed downwardly, means for retaining the body and the wrapper sheet in the said position while said elevating means is being withdrawn, means movable across the space between the plates for folding under one of the said opposite portions of the wrapper sheet, a pivotally mounted gate adapted to position in the trough adjacent to the open end, means for moving the gate into position at one side of the body and wrapper sheet while said folding means is functioning, a press plate, means for moving the press plate into position against the upwardly directed base of the body and wrapper, a pusher element movable through the opening of the second plate past said guide toward said gate, means for removing the gate in timed relation with said pusher whereby the pusher may move the body and wrapper into the trough to effect the folding of the opposite portion of the wrapper sheet under the body, and means for sealing the wrapper sheet as the body is moved by the pusher through the trough.

21. In a wrapping machine of the character described, a source of wrapping material supply, a vertically movable elevator mechanism, means for feeding a predetermined size of wrapping material over said elevator mechanism, the elevator mechanism comprising a cradle and relatively movable side grasping jaws therefor, means for moving the elevator mechanism upwardly against the wrapping material to a predetermined position, said cradle and side jaws having limited relative movement in the direction of rectilinear movement of the elevator mechanism, means for moving said side jaws toward one another to grip an article in the cradle for a period during the upward movement of the elevator mechanism, and means for arresting the upward movement of the jaws at the end of said period.

22. In a wrapping machine of the character described, a source of wrapping material supply, a vertically movable elevator mechanism, means for feeding a predetermined size of wrapping material over said elevator mechanism, said mechanism comprising an article receiving cradle having open sides and relatively movable side grasping jaws positioned at said open sides, said jaws being movable toward and away from one another, a supporting means for the cradle, a supporting means for the side jaws, means connected with said supporting means for raising the cradle and the side jaws together as a unit for a predetermined period and then arresting the movement of the side members only, and means for moving the side members toward one another to grip an article in the cradle during said period and then separating the jaws.

23. In a wrapping machine of the character described, a source of wrapping material supply, a vertically movable elevator structure, means for feeding a predetermined size of wrapping material over said elevator structure, said elevator structure comprising an article receiving cradle having open sides and relatively movable side members positioned at said open sides, a supporting means for the cradle, a supporting means for the side members, means connected with said supporting means for raising the cradle and the side members together as a unit for a predetermined period and then arresting the movement of the side members only, means for moving the side members toward one another to grip an article in the cradle during said period and then separating the members, and

said means for raising the side members effecting reverse movement of the side members following separation thereof and before the cradle reaches the limit of its upward movement.

5 24. In a wrapping machine of the character described, a source of wrapping material supply, a vertically movable elevator structure, means for feeding a predetermined size of wrapping material over said elevator structure, said elevator structure comprising a cradle, a body disposed therebeneath for up and down movement relative thereto and a pair of gripping side members pivoted on the body for cooperative movement to grip an article in the cradle, separate means connected with the cradle and the body for moving the cradle, the body and side members upwardly 10 as a unit for a predetermined period, said body moving means stopping its upward movement prior to the cradle moving means reaching its upward limit of movement, camming elements carried by said side members, and fixed actuators having said camming elements in sliding contact therewith, said camming elements effecting the closing of said side members upon an article in the cradle in the up travel of the elevator structure and the opening of the members as the body stops its upward movement.

25 25. In a wrapping machine of the character described, a source of wrapping material supply, a vertically movable elevator structure, means for feeding a sheet of wrapping material of predetermined size over the elevator structure, a pair of fixed sheet folding plates in face opposed relation above the sheet of material and spaced to have the elevator structure moved therebetween, the elevator structure including opposed relatively movable gripping fingers, means for closing said fingers on an article in the elevator structure until the structure has raised to a predetermined elevation between said plates, means for releasing and reversely moving the fingers when said elevation is reached, means for withdrawing the elevator structure from beneath the elevated and finger released article, a horizontally movable plate at one side of the top edge of one of the pair of plates, means for moving the horizontally movable plate a slight distance across the said top edge of the said one of the pair of plates to support the article while the elevator structure is being withdrawn, and means for folding the sheet around the article.

40 26. A wrapping machine as set forth in claim 25, with means for continuing the horizontal movement of said movable plate completely across the space between said pair of plates to fold under one side of the wrapper sheet and simultaneously support the article.

35 27. A wrapping machine as set forth in claim 25, wherein in said opposed plates have vertical recesses in their opposed faces for receiving the gripping fingers when the latter are released from the article.

50 28. A wrapping machine as set forth in claim 25, wherein in said opposed plates are downwardly and laterally curved to facilitate the upward movement of the article and wrapping the sheet therebetween.

60 29. A wrapping machine as set forth in claim 25, with means for continuing the horizontal movement of said movable plate completely across the space between said pair of plates to fold under one side of the wrapper sheet and simultaneously support the article, spaced vertical shoes disposed above the said top edge of the said one of the pair of plates for engagement by one side of the wrapper sheet and article, a gate plate formed to position above the other one of the pair of plates, means movable between the shoes to move the article and sheet horizontally off of and in the direction of first movement of the movable plate, and means for positioning the gate plate against the other side of the wrapper sheet and article prior to the initial movement of said movable plate and for removing the gate plate from said position in synchronization with the movement of the means by which the article is moved off of the movable plate.

70 30. In a machine of the character stated, an elevator mechanism for raising a body composed of a number of separable parts to a predetermined position, said mechanism comprising a pair of vertically positioned rods, a guide means for holding the rods in position for vertical reciprocation, independent means for reciprocating the rods, a body supporting cradle carried by one rod, a head block carried by the other rod, a pair of opposed gripping jaws pivotally supported on the head block and spaced to have said cradle moved to a position therebetween whereby a body in the cradle may be grasped between the jaws, an elongate cam rod of irregular longitudinal contour depending from each jaw, and fixed position cam

members each engaged and traversed by a cam rod in the reciprocal movement of the head block for effecting grasping and releasing movements of the jaws in timed sequence with relative rectilinear movements of the jaws and cradle.

31. The invention as set forth in claim 30, wherein said head block has a guide opening through which the cradle supporting rod passes freely.

32. The invention according to claim 30, wherein said vertically positioned rods are of polygonal cross section providing longitudinal flat faces, and said guide means for each rod comprises a plurality of roller members equi-distantly spaced around the rod and each having rolling contact with one of said flat faces.

33. The invention as set forth in claim 30, wherein said cam members comprise two spaced rollers between which said cam rods pass and a spring connected between said jaws and constantly tending to pull the same together to maintain the cam rods in sliding contact with the rollers.

34. In a machine for wrapping bodies made up of at least two flat portions such as sandwiches, a wrapping sheet receiving table having an opening over which a wrapping sheet is placed, a body receiver above the table comprising two spaced vertical plates having the opposed faces substantially in the plane of opposite edges of said opening, the bottom edges of the plates being downwardly and laterally curved, said plates having aligned openings therein, a plurality of spaced vertical shoes in one plate opening, a body receiving trough aligned with and leading from the other plate opening, mechanism for grasping the flat sides of a body and raising the same through the table opening to pick up a wrapping sheet therefrom and raise the body and sheet together into said receiver between the plates, whereby said curved edges of the plates fold down the wrapping sheet across opposite sides of the body, the mechanism bringing the body and sheet to rest against said shoes and in line with the trough opening, means movable toward the trough opening from below the shoes for engagement under an edge of the body to support the body while the raising mechanism is removed, a moving endless chain disposed above and parallel with

the trough and extending across the receiver, a plurality of body pushers carried by the chain to move successively past the shoes and across the space between the plates, a swinging gate positioned to move into the trough and

5 into said other plate opening to press against the body and wrapper to hold the latter against said shoes and coact with the said body supporting means, means for continuing the movement of the body supporting means across the receiver to fold under one side of the wrapping sheet, and mechanism moving said chain and gate in proper sequence to remove the gate from the trough and move the pusher into contact with the wrapper sheet and body to slide the body into the trough off of the said body supporting means.

35. The invention according to claim 34, with a plurality of yieldably supported press plates carried by the endless chain each in advance of a pusher and adapted to yieldingly press down upon the top edge of the body, while the said body supporting means is moving across 20 beneath the body.
